ATTORNEY.

UNITED STATES PATENT OFFICE

ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

CYLINDER HEAD

Application filed November 7, 1927. Serial No. 231,420.

This invention relates to internal combustion engines and refers more particularly to an engine of the sleeve valve air cooled type.

One object of my invention resides in providing an improved cylinder head cooling means in the air cooled sleeve valve type of engine. In carrying out my invention I provide a cylinder head formed with a closed jacket containing a body of suitable liquid 10 adapted to be vaporized under the influence of the heat of the combustion chamber, the heat absorbed by the liquid being transferred and dissipated by travel of the vapor to a suitable cooling surface. By reason of such 15 an arrangement I have provided a self-contained cylinder head cooling system.

In an air cooled engine little difficulty is experienced in maintaining the cylinder proper at the desired temperature, but difficulty is experienced in adequately cooling the cylinder head, especially in the sleeve valve type of engine. In this type of engine the spark plug is ordinarily positioned within the recessed portion of the cylinder head where 20 it and the cylinder head proper are not adequately cooled. By reason of my invention the customary recessed or pocket construction of the cylinder head may, if desired, be eliminated with the spark plug located generally well above the cylinder head where it 25 may be maintained in the desired cooled condition.

Further features of my invention reside in the novel combination and arrangement of 30 parts more particularly hereinafter described and claimed.

Referring to the accompanying drawing, the single figure illustrates a section through a typical cylinder showing one embodiment 35 of my invention.

Reference character A illustrates one of the engine cylinders formed with the cooling ribs or fins 10 and sleeve valve 11, the latter for illustration being shown as the "Burt-McCollum" single sleeve valve type in which the sleeve is moved in a combined reciprocating and oscillating path with respect to the sleeve axis in moving sleeve ports 12 to function with the cylinder ports 13. My invention is 40 not directed to any particular arrangement

of sleeve valves or ports thereof and is equally useful in connection with other well known types of sleeve valve and other engines.

The cylinder A is closed by a cylinder head B which may be constructed of a head portion 14 and a cooperating cover portion 15. The portion 14 is flanged at 16 for seating on the cylinder A and has a substantially cylindrical wall 17 depending within the cylinder and spaced therefrom to provide a sleeve pocket 18 accommodating the upper end of the sleeve valve 11. The cylinder head has a second substantially cylindrical wall 19 extending upwardly from, and spaced within, the wall 17 to form a jacket 20. The wall 19 further forms the combustion chamber 21, a spark plug 22 being preferably located at the top thereof so as to extend well above the cylinder head heat zone. The jacket 20 is suitably enclosed by the cover portion 70 55 60 65 70 75 80 85 90 95 100 15, the joints 23 and 24 being welded or otherwise sealed. The cylinder head B is secured to the cylinder by the fasteners 25. Cooling fins 26 are arranged on the cover portion 15 extending transversely to the direction of travel of the cooling air stream, where such a stream is employed, as indicated by the arrow.

Within the jacket enclosure 20 is a body of suitable liquid 27 such as mercury, the walls of the jacket preferably being coated with amalgam 28 or the like to facilitate the heat transfer relatively between the mercury and the jacket walls.

In operation the heat developed in the combustion chamber 21 and associated parts will be transferred to the body of liquid 27 causing the latter to be vaporized. The vapor will rise, striking the portion 15 which is maintained in a relatively cool condition by reason of cooling fins 26 and the general remoteness thereof from the combustion chamber. The vapor on striking the portion 15 will be condensed, giving up its heat thereto, the condensate running back to the main body 27. The vapor within the jacket enclosure will serve to maintain the jacket walls exposed thereto in the desired cool condition.

Various substances may be utilized in place of mercury, it being only necessary 100

that such substance vaporizes within the temperature limits of ordinary engine operations so that excessive temperature will not result.

5. What I claim as my invention is:

1. In an internal combustion engine, a cylinder, a cylinder head formed with a jacket enclosure, a combustion chamber and associated spark plug, and cylinder head cooling means including a cooling liquid within said jacket enclosure adapted to be vaporized by the heat generated by the engine.
10. In an internal combustion engine, a cylinder, a cylinder head provided with a sealed jacket enclosure, a combustion chamber and associated spark plug and cylinder head cooling means comprising a cooling liquid within said enclosure.
15. In an internal combustion engine of the air-cooled spark ignition type, a cylinder, a cylinder head provided with a sealed jacket enclosure, heat dissipating means associated with the cylinder head, and a cooling liquid within the jacket enclosure adapted to be vaporized by the heat generated by the engine, said heat dissipating means being positioned for condensing the vapor.
20. In an internal combustion engine of the air-cooled spark ignition type, a cylinder, a cylinder head provided with a sealed jacket enclosure, heat dissipating means associated with the cylinder head, and a cooling liquid within the jacket enclosure adapted to be vaporized by the heat generated by the engine, said heat dissipating means being positioned for condensing the vapor.
25. In a sleeve valve engine the combination with a cylinder, of a head having a jacket enclosure depending within the cylinder and spaced therefrom to form a sleeve pocket, sleeve valve means within said pocket, and a body of cooling liquid within said jacket adapted to be vaporized by the engine heat.
30. In a sleeve valve engine the combination with a cylinder, of a head having a jacket enclosure depending within the cylinder and spaced therefrom to form a sleeve pocket, sleeve valve means within said pocket, and a body of cooling liquid within said jacket adapted to be vaporized by the engine heat.
35. In a sleeve valve engine the combination with a cylinder, of a head having a jacket enclosure depending within the cylinder and spaced therefrom to form a sleeve pocket, sleeve valve means within said pocket, said head provided with a jacket cover having cooling projections, and a cooling liquid within said jacket adapted to be vaporized by the engine head, said jacket cover serving to condense the vapor.
40. In an internal combustion engine, of the air cooled spark ignition type, a cylinder, a cylinder head formed with a jacket enclosure, and a body of mercury within the jacket adapted to be vaporized by the heat generated by the engine.
45. In an internal combustion engine, of the air cooled spark ignition type, a cylinder, a cylinder head formed with a jacket enclosure, and a body of mercury within the jacket adapted to be vaporized by the heat generated by the engine.
50. In an internal combustion engine, a cylinder, a cylinder head formed with a jacket enclosure, and a body of mercury within the jacket adapted to be vaporized by the heat generated by the engine, the walls of said jacket having a coating of amalgam.
55. In a sleeve valve engine the combination with a cylinder, of a head having a substantially cylindrical wall depending within the cylinder and spaced therefrom to provide a sleeve pocket, a second wall joined with the first said wall and extending upwardly therewithin and spaced therefrom, a cover forming with the said walls an enclosed cooling jacket, and a coolant trapped

within said jacket enclosure and circulating solely therein.

9. In a sleeve valve engine the combination with a cylinder, of a head having a substantially cylindrical wall depending within the cylinder and spaced therefrom to provide a sleeve pocket, a second wall joined with the first said wall and extending upwardly therewithin and spaced therefrom, a cover forming with the said walls an enclosed cooling jacket, and a coolant trapped within said jacket enclosure, said cylinder and cover provided with air cooled ribs.

10. In a sleeve valve engine, a cylinder, and a cylinder head spaced from the cylinder to provide a sleeve pocket and having an enclosed cooling jacket depending therewithin bearing a cooling medium circulated solely within said jacket.

11. In an air cooled sleeve valve engine, a cylinder having cooling ribs, a cylinder head depending within said cylinder and spaced therefrom to provide a sleeve pocket, said cylinder head provided with cooling fins and spark plug extending for the most part beyond the outer limits of said cylinder head.

12. In an air cooled sleeve valve engine, a cylinder, and a cylinder head depending within said cylinder and spaced therefrom to provide a sleeve pocket, said cylinder head provided with cooling fins and spark plug extending for the most part into the path of the air stream directed against the cooling fins.

13. In an air cooled sleeve valve engine, a cylinder, and a cylinder head depending within said cylinder and spaced therefrom to provide a sleeve pocket, said cylinder head having cooling fins and means for circulating a cooling medium adjacent the depending portion of the cylinder head, and provided with a spark plug extending for the most part into the path of the air stream directed against the cooling fins.

14. In an internal combustion engine, a cylinder, and a cylinder head formed with a jacket enclosure and provided with a combustion chamber and with means for igniting the fluid in said combustion chamber, said cylinder head bearing a heat absorbent and heat transmitting fluid circulating solely within said jacket enclosure.

15. In an internal combustion engine, a cylinder, and a cylinder head formed with a sealed jacket enclosure bearing a heat absorbent and heat transmitting fluid.

In witness whereof, I hereunto subscribe my name this 2nd day of November, A. D. 1927.

ARCHIE MACPHAIL NIVEN.
